UNITED STATES PATENT OFFICE.

MINTER P. KEY, OF MEMPHIS, TENNESSEE.

MACHINE-GUN

SPECIFICATION forming part of Letters Patent No. 241,671, dated May 17, 1881.

Application filed March 23, 1881. (No model.)

To all whom it may concern:

Be it known that I, MINTER P. KEY, a citizen of the United States, residing at Memphis, in the county of Shelby and State of Tennessee, have invented certain new and useful Improvements in Machine or Field-Battery Guns; and I do hereby declare the following to be a full, clear, and exact description of the invention, such as will enable others skilled in the art to which it appertains to make and use the same, reference being had to the accompanying drawings, and to the letters or figures of reference marked thereon, which form a part of this specification.

My invention relates to certain new and useful improvements in the class of machine or battery guns employing a series of barrels arranged side by side on the same horizontal plane; and the invention has for its object the production of a gun in which the fire from several cases, each containing a series of barrels, can be concentrated at any given point and in different or the same horizontal planes, and also to sweep the segment of a circle; and to this end the invention consists, essentially, in a series of pivoted cases arranged one above the other on the same axis, each case containing a series of barrels arranged side by side, in combination with a carriage and a stationary case or box having a similar series of barrels arranged on said carriage; and the invention further consists in novel features of construction, and combination and arrangement of parts, all as will be hereinafter fully described, and specifically pointed out in the claims.

Referring to the accompanying drawings, Figure 1 represents a top view or plan of my improved gun with the top shield of the armor removed; Fig. 2, a longitudinal vertical section; Fig. 3, detail horizontal section of one of the cases or boxes containing a series of barrels; Fig. 4, cross-section of Fig. 3; Fig. 5, a rear elevation, with the side shields broken away; Fig. 6, a longitudinal vertical section through the series of cases or boxes, showing the adjusting mechanism for elevating or lowering the cases at either or both ends thereof. Fig. 7 is a side elevation, with one of the wheels removed.

In the drawings, A A represent the supporting-wheels, connected by the usual axle, B,

and C a metallic box in which said axle rests, said box having horizontal projecting flanges e e at the upper end thereof, to which the supporting or bed plate D is bolted or otherwise secured. The inner side of the box C is made circular in form to correspond with the contour of the axle, so that said box can be oscillated or turned thereon in order to elevate or depress the bed-plate upon which the cases or boxes containing the series of barrels are arranged, as will now be described.

E F G represent cases or boxes, each provided with a series of barrels, e f g, arranged side by side, and soldered or otherwise secured together. These boxes or cases are arranged one above the other, the lower case or box, E, being stationary, and the upper ones, F G, pivoted or journaled on the same vertical axis H, so that either one of the cases or boxes F G can be turned independently of the other, and respectively to the right and left, so that the cases or boxes when in such position are fan-like in form, and the fire therefrom adapted to sweep the segment of a circle, as clearly shown in Fig. 1. The vertical axis or shaft H, upon which the cases or boxes F G are journaled, has shoulders f' g', upon which they are supported and adjusted, as shown in Fig. 6. The axis or shaft H passes down through the case E, and has a screw-thread, h, thereon, near the lower end, which works in a screw-threaded portion, e', and also a hand lever or wheel on the lower end, by which it can be turned, and thus elevate or depress the pivoted cases F G at their rear ends.

Between the cases or boxes, near their front ends, are arranged pivoted cams a a, which may be operated from the rear of the gun by any suitable means for elevating or depressing said cases or boxes F G at their front ends.

By the above-described arrangement of the pivoted cases or boxes and their adjusting mechanism, the fire from the barrels of the several cases or boxes can be concentrated at any given point desired, or on different horizontal planes, and also to sweep the segment of a circle.

By adjusting the cases or boxes F G relatively to each other and to the case or box E, as shown in Fig. 6, the distance between their horizontal planes is increased, and, through the medium of the front and rear adjusting

mechanism, the upper cases or boxes, F G, can be adjusted so as to depress their front ends and concentrate the fire from the barrels of the several cases, or adjusted so as to depress the rear ends thereof, and thus elevate their front ends so that the fire from the barrels of each of said pivoted cases will be at an angle or upward inclination to the fire from the barrels of the lower or stationary case, E. These 5 adjustments of the cases or boxes F G permit the range of the fire from the barrels of the several cases or boxes to be so regulated as to cover platoons in rear of each other, and which, especially in advancing up or down hill, could 10 be made very effective. The cases or boxes are provided with inlet-openings *i* for the admission of water or other suitable fluid, to surround and prevent undue heating of the barrels when under rapid fire, and outlet or discharge openings *j*, to permit the withdrawal or discharge of the water or other fluid when desired. The cases or boxes are also provided, 15 on the sides thereof, with telescopes I, as shown in dotted lines, Fig. 1, in order to get the proper 20 charge. The stationary box or case E may be dispensed with, if desired, and the number of stationary and pivoted boxes or cases increased, 25 without departing from the spirit of my invention.

In order to protect the men operating the gun, as well as the horses, I provide a novel arrangement of armor, as will now be described.

J represents the bottom shield of the armor 30 pivoted to the box C or axle, and inclining rearward and downward at the proper angle to cause any balls striking it to glance downward toward the ground.

K K represent the side shields of the armor 35 pivoted to the axle or box C, on opposite sides of the cases or boxes E F G, and extending from or near the ground a short distance above the upper case or box, G, and inclined or beveled off on their top ends, *l*, for a purpose to 40 be hereinafter described. These side shields extend rearward and outward from their pivotal point at the proper angle, so that any balls striking them will glance off or away 45 from the gun.

L represents the top shield of the armor pivoted to the axle or box C, and cut away for the cases or boxes, as shown in Fig. 5, so that it may be turned over on the upper case or box G when the gun is not under fire. This 50 shield inclines rearward and upward at the proper angle, so that any ball striking it will glance upward and over the men operating the gun. When the shield L is in proper position it is supported both by the rods *l* and 55 the side shields, K K, upon which its extreme edges rest, as shown more clearly in Fig. 7, the beveled or inclined top edges of the side shields corresponding to the angle of the top shield.

The top shield is provided with an opening, M, for observation, and which is closed by a metallic slide, *m*.

In order to permit of the necessary side play of the pivoted boxes or cases F G, the top shield is provided with openings *n n*, which are closed when said cases or boxes are in line 70 with the lower case or box, E, by means of the automatic slides *n' n'*, operated through the medium of the springs *o o*, which press or bear against the rear ends of said slides, so that their front ends are always pressed against 75 the sides of said boxes or cases, as clearly shown in Fig. 5.

The manner of loading and firing the barrels of the several cases or boxes of my improved gun is not deemed essential in this case, 80 as it will form the subject-matter of a subsequent application for Letters Patent.

Having thus fully described my invention, what I claim as new, and desire to secure by 85 Letters Patent, is—

1. In a machine or battery gun, a series of pivoted cases or boxes arranged one above the other on the same axes, and each case or box containing a series of barrels arranged side by side, in combination with a carriage and a 90 stationary case or box having a similar series of barrels arranged on said carriage, substantially in the manner as, and for the purpose herein shown and described.

2. In a machine or battery gun, the combination of a stationary case or box, a series of pivoted cases or boxes arranged one above the other on the same axis, and each case or box provided with a series of barrels arranged side by side, and mechanism, substantially as described, for adjusting said pivoted cases relatively to each other, and the stationary case or box arranged between said cases near their front ends, substantially as and for the purpose specified.

3. In a machine or battery gun, the combination, with the pivoted cases or boxes, of the top shield of the armor, having openings *n n* arranged in the opposite side edges thereof, and automatic-closing spring-slides *n' n'*, substantially as and for the purpose specified.

4. In a machine or battery gun, the armor consisting of the bottom shield, *J*, side shields, *K K*, and top shield, *L*, having openings arranged in the opposite side edges thereof, and automatic-closing spring-slides, all pivoted to the axle or box C, and arranged relatively to each other, and the pivoted cases or boxes, substantially as herein shown and described.

In testimony whereof I affix my signature in presence of two witnesses.

MINTER P. KEY.
